atty.

UNITED STATES PATENT OFFICE.

SHERWIN M. COAN, OF ALLSTON, MASSACHUSETTS.

SPRING WHEEL.

Application filed March 21, 1925. Serial No. 17,193.

To all whom it may concern:

Be it known that I, SHERWIN M. COAN, a citizen of the United States, residing at Allston, in the county of Suffolk and State 5 of Massachusetts, have invented certain new and useful Improvements in Spring Wheels, of which the following is a specification.

My invention relates to spring wheels for vehicles and has for its essential objects the 10 absorption of both radial and transverse strains and shocks, including the peripheral strain exerted by the vehicle in turning a corner, and the sudden checking of the advance of the vehicle. Further objects are 15 strength, inexpensiveness of construction, and such further advantages and capabilities as will more fully appear hereinafter.

My invention consists, therefore, in the means and mechanism for producing the results above specified substantially as hereinafter claimed.

In the accompanying drawings which form a part of this specification

Figure 1 is a rear elevation with parts 25 broken away.

Figure 2, a diametrical section on line 2—2 of Figure 1.

Like reference characters indicate like parts throughout the views.

30 The structure as herein illustrated comprises circular front and back plates or walls 4 and 5 provided respectively with central circular openings 6 and 7 respectively. The former is closed by a convex plate 8 attached by bolts 9 to the plate 4 or integral therewith. Attached to the peripheral margins of the plates 4 and 5 by screws 10 is a felly or rim 11 carrying a tire 13. In intermediate portions of the walls are annular 35 series of holes 15 for the reception of transversely disposed rods 16 having projecting threaded ends carrying nuts 18 bearing against the exposed faces of the walls. In this instance sleeves or bushings 19 on the rods have their ends abutting against the inner faces of the walls. Surrounding each rod is a double cone spring 21, whose intermediate helices 22 are the larger, and whose end helices 23 embrace the enclosed bushing 40 and abut against the housing walls.

A hub ring 25 is provided consisting in this instance of two annular members 26 united by rivets 27 to the margin of a central opening 28 in the body 29 of a circular disk or diaphragm 30. The disk has a lat-

eral peripheral flange 32, and the body is provided intermediate its center and the flange 32 with an annular bend forming an intermediate lateral shoulder 34 and a transversely inclined web or connecting portion 35. The shoulder 34 is concentric with and parallel to the flange 32. The portion 35 has radially disposed circular openings 37 arranged to admit therethrough the springs 21. The helix having the greatest 65 diameter in each spring contacts with both the flange 32 and the shoulder 34, and is attached to the flange and shoulder by U bolts 38 and 39 respectively.

In operation the yielding relation of the 70 member 30 to the body of the wheel, cushions or absorbs not only shocks such as external blows from any direction upon the wheel, but internal shocks due to the operation of clutches, or brakes, or otherwise.

It will be observed that the springs are 75 separately removable for inspection or repair, and that all parts are readily accessible.

I claim:—

1. In a spring wheel, a front housing wall, a back housing wall provided with a central opening, a rim attached to the walls, annularly arranged transversely disposed rods fixed in the walls, helical springs surrounding the rods, a disk between the walls provided with a central opening, a laterally extending peripheral flange upon the disk, an annular shoulder upon an intermediate portion of the disk concentric with the flange, said disk being provided with openings to allow passage of the springs therethrough, means for attaching the sides of the springs to the flange and shoulder, and a hub ring surrounding the central opening 95 of the disk.

2. In a spring wheel, a front housing wall, a back housing wall provided with a central opening, a rim attached to the peripheries of the walls, said walls being provided with annularly disposed holes, transverse rods provided with threaded end portions projecting through the holes, nuts on the threaded portions of the rods, sleeves on the rods with their ends abutting against the walls, helical springs surrounding the rods, a disk between the walls provided with a central opening, a peripheral flange upon the disk, a shoulder upon an intermediate portion of the disk, said disk being provided 100 105 110

with openings to admit the springs, means for attaching the springs to the flange and shoulder, and a hub surrounding the central opening of the disk.

- 5 3. In a spring wheel, a front housing wall provided with a central opening, a rim connecting the walls, annularly arranged transverse rods connecting the walls, springs surrounding the rods comprising helices, a disk
10 between the walls provided with a central opening, a peripheral flange upon the disk,

a shoulder upon an intermediate portion of the disk, said disk being provided with openings around the springs, **U** bolts in the flange securing the springs to the flange, **U** bolts on the shoulder securing the springs to the shoulder, and a hub ring surrounding the central opening of the disk.

In testimony whereof I have affixed my signature.

SHERWIN M. COAN.
